[57] CLAIM

The ornamental design for a front panel for optical
drive, as shown and described.

DESCRIPTION

FIG. 1 is a top front side perspective view of a front
panel for optical drive showing our new design;
FIG. 2 is a right side elevational view thereof;
FIG. 3 is a left side elevational view thereof;
FIG. 4 is a front elevational view thereof;
FIG. 5 is a top plan view thereof;
FIG. 6 is a rear elevational view thereof;
FIG. 7 is a bottom plan view thereof.
FIGS. 2-7 are shown on an enlarged scale.

FIG. 1
